UNITED STATES PATENT OFFICE.

JOHN BRADLEY, OF CHELMSFORD, MASSACHUSETTS.

KNITTING-LOOM.

SPECIFICATION forming part of Letters Patent No. 538,653, dated May 7, 1895.

Application filed April 10, 1894. Serial No. 506,987. (No model.)

To all whom it may concern:

Be it known that I, JOHN BRADLEY, of North Chelmsford, in the county of Middlesex and State of Massachusetts, have invented certain 5 new and useful Improvements in Knitting-Looms, of which the following is a specification.

This invention has relation to machines for producing warp-and-weft fabrics by the knitting process; and it has for its object the production of improved means for laying in the warp and weft threads, so that the web may closely resemble a fabric produced upon an ordinary loom employing harness to control 15 the warps and a shuttle and lay to put in the weft.

To these ends the invention consists of the improvements which I will now proceed to describe and claim.

20 Reference is to be had to the annexed drawings and to the letters marked thereon, forming a part of this specification, the same letters designating the same parts or features, as the case may be, wherever they occur.

25 Of the drawings, Figure 1 is a plan view of my improved knitting-loom. Fig. 2 is a vertical central sectional view of the same. Fig. 3 is a detail view, in front elevation, showing the manner of laying in the weft-thread and 30 of guiding and controlling the warps. Fig. 4 is a cross-sectional view of the upper portion of what is shown in Fig. 3.

In the drawings—*a* designates the bed or frame of the machine.

35 *b* is the needle head supported upon a strap, *c*, connected at its ends with the bed, and adapted to turn on the bolt, *d*, connected at its lower end to the said strap and extending centrally through the head.

40 *e* are spring-beard needles carried by the head in the usual way so that ordinary knitting may be performed thereon as the head is rotated with the co-operation of a yarn-guide, *f*, stitch-wheel, *g*, presser-wheel, *h*, and 45 other essential contrivances.

The head, *b*, is provided on its lower edge with bevel gear-teeth, *i*, which may be integral with the head or form a part of a gear attached to the bottom of the head, which 50 gear-teeth are engaged by the teeth of a bevel gear, *j*, secured to the driving shaft, *k*. By this means the head is adapted to be rotated.

l designates a revoluble warp carrier having bearings on the bed, *a*, and provided in its lower part with bevel teeth *m*, which are 55 engaged by the teeth of the bevel gear, *n*, on the driving shaft, *k*.

The teeth of the gears, *n*, and, *j*, agree in number as do also the teeth, *i*, and, *m*, so that the head and warp-carrier will be moved in 60 exact unison.

The warp-carrier is equipped with a number of spools, *o*, carrying threads in number equal to the number of needles in the head, which warp threads are led from their spools 65 through guide-ways, *p*, (formed in the vertical cylinder, *r*, forming an integral part of the warp-carrier) beneath a tension ring, *s*, through guide notches, *t*, formed in the upper edge of the cylinder, *r*, between the needles, and into the fabric longitudinally thereof. There is a warp thread extending between each two needles.

Between the cylinder, *r*, and the head, *b*, there is a space, and in this space and attached to the stationary bed of the machine there is arranged a weft-guide and warp-raiser *u*, extending to or slightly above the tops of the needles, and guiding a thread, *v*, led up through a hole in the bed, *a*, and 75 through the space between the cylinder, *r*, and head, in such manner as to lay said thread, *v*, on or over the tops of the needles behind the warp threads, *w*, and in front of the stitches in the hooks of the needles, formed 80 from the regular knitting-thread, *x*. The weft-guide, *u*, is so constructed that it raises the warp threads slightly at the tops of the needles so that the weft thread may be laid in, as described.

90 *y'* designates a warp depressor arranged in the space between the carrier and head, *b*. It is attached to the stationary bed of the machine and located in the vicinity of the stitch-forming mechanism, as shown in Fig. 1. Its 95 function is to depress the warp threads below and past the stitch wheel. Otherwise, the warp threads become entangled with the stitch-wheel.

y designates the ordinary push back arranged to crowd the stitches down upon the stems of the needles with the weft thread lying behind the same as shown in Fig. 1.

z is the clearing wheel having the usual

function, arranged in advance of the stitch-wheel.

The construction and arrangement of parts whereby I am enabled to lay the weft between the warp and knit stitches are the principal features distinguishing my invention from the prior art.

The fact that the regular knitting thread is introduced into the needles in front of the warp thread so as to bind the warp threads to the regularly knitted body, and so as to draw the regular knitted loops between the warp threads and behind the weft thread, gives to the face of the fabric an appearance which, to other than a highly skilled expert, has the appearance of a regularly woven cloth formed by the process of weaving.

Having thus explained the nature of the invention and described a way of constructing and using the same, though without attempting to set forth all of the forms in which it may be made or all of the modes of its use, it is declared that what is claimed is—

1. A knitting loom comprising in its construction a knitting mechanism adapted to form a regular knitted web, warp-guides for guiding the warp threads between the needles, and a combined warp raiser and weft guide having a part to raise the warp threads above the needles and a slot to guide a weft thread beneath the warp threads and between the warp threads and the loops of the knitted thread.

2. A knitting loom comprising in its construction a knitting mechanism adapted to form a regular knitted web, warp guides for guiding warp threads between the needles, and a combined warp raiser and weft guide extending between the warp threads and the needles, and having a part to raise the warp threads and a slot to lay the weft thread behind the warp threads and back of the regular knitted loops.

3. A knitting loom comprising in its construction a rotary head and its needles, and co-operating spring beard needle knitting mechanism for forming a regularly knitted web, a warp carrier and independent means for moving it in unison with the head, and a combined weft-guide and warp-raiser arranged between the head and carrier having a part to raise the warp thread above the needles and a slot to guide a weft thread beneath the warp threads and between the warp threads and the loops of the knitted thread, substantially as and for the purpose described.

4. A spring-beard needle knitting loom comprising in its construction a head and its needles, and means for rotating the head, and co-operating knitting mechanism for forming a regularly knitted web, a warp carrier independent of said head and means for moving it, and a combined warp-raiser and weft-guide having a part to raise the warp threads above the needles and a slot to guide a weft thread beneath the warp threads and between the warp threads and the loops of the knitted threads, substantially as and for the purpose described.

5. In a spring-beard knitting loom, the combination of a needle cylinder, a warp carrier surrounding said cylinder and in the same horizontal plane therewith, and independent means for rotating said cylinder and carrier, said carrier being provided with an upwardly extending flange provided with a thread tension device and notches to guide the warp thread, substantially as and for the purpose described.

6. The combination, with the rotary head, of the warp-carrier revolvable around the head, independent means for moving the head and carrier in unison, and a stationary weft-guide and warp raiser extending upward between the head and carrier and having a part projecting above the needles, substantially as and for the purpose set forth.

7. In a knitting loom in combination, a rotary head and its needles and complementary stitch-forming mechanism, an independently revolvable warp carrier, a weft guide and warp raiser having a part projecting above the needles and a weft guiding slot and a warp depressor.

8. In a knitting loom, in combination, a rotary head, a revolvable warp-carrier, independent means for moving the head and carrier, complementary stitch-forming mechanism comprising a stitch-wheel, a weft guide, and a stationary warp-depressor located between the head and carrier near the stitch-wheel to guide the warp threads below and clear of the stitch-wheel, substantially as and for the purpose set forth.

In testimony whereof I have signed my name to this specification, in the presence of two subscribing witnesses, this 7th day of April, A. D. 1894.

JOHN BRADLEY.
